UNITED STATES PATENT OFFICE

ALBIN HJELM, OF CHICAGO, ILLINOIS, ASSIGNOR TO BRITESUN, INC., OF CHICAGO,
ILLINOIS, A CORPORATION OF ILLINOIS

AUTOMATICALLY-ADJUSTED CARBON-ARC LAMP

Application filed August 24, 1928. Serial No. 201,780.

This invention relates to improvements in an automatically adjusted carbon arc lamp especially for therapeutic purposes, and has for one of its principal objects the provision of means for automatically maintaining the terminals of a pair of carbon electrodes at a desired fixed distance from each other, the burning away of the ends of the carbons being compensated for by means of a feed mechanism including a solenoid.

One of the important objects of the invention is to provide a carbon feed mechanism which will movably retain the carbon electrodes in operative position and will reduce vibration of the said carbon electrodes to a minimum.

It is common knowledge among those skilled in the art that the magnetic field intensity produced by a solenoid is directly proportional to the current flowing through the solenoid and that consequently the force exerted by the field upon a movable core contained within the solenoid will cause the core to move against a constant resisting force a distance directly proportional to the current flowing in the solenoid. It is also well known that the relation between the variation of the length of a carbon arc gap and the variation of the current flowing thereacross is not a linear one. Applicant's device accordingly provides means for compensating for this difference of relative movements, namely the linear relationship of the current to the solenoid core movement and the non-linear relationship of the current to the carbon gap length. The said means comprises a combination lever and cam carbon feed mechanism which will smoothly move the carbons together as they burn away eliminating any tendency of the carbons to oscillate or vibrate until an equilibrium is reached, as is the case where the solenoid core and the carbon move in a linear relation to each other.

A further important object of the invention is to provide an electrically operated damping means for retarding the motion of the solenoid core and a manual adjustment for the damping means thereby regulating the length of the arc gap which tends toward

stability and flexibility of operation.

Another and still further important object of this invention is the provision of means for positively electrically connecting the movable carbons in the arc circuit and maintaining this positive contact regardless of the temperature of the connecting elements, said means comprising a metal clip which contracts when heated in contradistinction to the characteristics of the connecting clips heretofore used which expand when heated and form an imperfect contact with the carbon.

Other and further important objects of the invention will be apparent from the disclosures in the accompanying drawings and following specification.

The invention, in a preferred form, is illustrated in the drawings, and hereinafter more fully described.

In the drawings:

Figure 1 is a side elevation, partly in section and parts being broken away, of the improved carbon arc lamp of this invention.

Figure 2 is a front elevation of the illuminating unit, illustrating in particular the positioning of the carbons in front of the reflector.

Figure 3 is a rear elevation of the illuminating unit showing particularly the automatic carbon feed mechanism.

Figure 4 is a fragmentary side sectional view of the electrical damping means.

Figure 5 is a sectional view taken on the line 5-5 of Figure 4.

Figure 6 is a detail sectional view of a portion of the feed mechanism, illustrating in particular the improved carbon clutch.

Figure 7 is a detail elevation, parts being broken away, of a portion of the feed mechanism, showing particularly the carbon feed cam.

Figure 8 is a sectional view taken on the line 8-8 of Figure 6.

Figure 9 is a detail view of a modification of the improved carbon clip.

As shown in the drawings:

The reference numeral 10 indicates generally a reflector or casing for a carbon arc therapeutic lamp, the same being preferably

constructed of a light durable metal capable of taking a high polish. A bracket 12 is riveted or bolted to the lower portion of the reflector and is adapted to be adjustably mounted upon a suitable support, not shown in the drawings. The top portion of the reflector is provided with a ventilating opening 14 and positioned thereabove is a canopy or shield 16 to prevent the undesirable escape of the light rays from the interior. 10 Surmounted upon the rear portion of the reflector 10 is a cylindrical cap 18, preferably made of a slightly heavier material than that comprising the reflector casing proper.

15 Suitably mounted within the casing 10, by means of lugs 20, best shown in Figure 3, and a lug 22, shown in Figure 1; and adapted to be bolted to the inner sides of the said reflector, is an illuminating unit A.

20 The unit A is preferably constructed as a unitary structure built around a frame plate 24, preferably of a light durable material such as aluminum or the like. It is not essential that this plate be metal but it must present heat resisting qualities characteristic of a metal. Bolted or otherwise suitably fastened to one face of the plate 24 is a reflector plate 26 and inserted therebetween is a layer of heat insulating material such as asbestos or the like 28. The purpose of the material 28 is to reduce the heat transfer from the plate 26 to the frame 24 to a minimum. Another means for decreasing this aforementioned heat transfer is the provision of an opening 30 in the central portion of the plate 24, air, as is well known, being a good heat insulating medium.

40 Referring particularly to Figures 1 and 2, a pair of carbon clamps 32 is rigidly mounted upon the face of the reflector plate 26, each being adapted to hold a carbon pencil 34. The mounting provided for the clamp 32 comprises a metal block 36 upon the face of which is positioned a strip of insulating material 38 such as mica or the like. A screw 40 holds the member 32 rigidly in contact with the insulating strip 38 and consequently retains the block 36 in desired position upon the plate 24. The screw 40 is insulated from both the plates 24 and 26 as is the member 32. Hence a perfect thermionically and electrically insulated electrode is provided for the fixed carbons 34.

50 A pair of vertically movable carbons 42 is positioned adjacent the fixed carbons 34, the ends of the carbons 42 and 34 abutting, whereupon the carbon arc is adapted to be struck when the carbons are energized.

60 The carbons 42 are slidably mounted in a pair of insulating bushings 44, best shown in detail in Figure 6, which are in turn rigidly mounted in a supporting framework

46 fixed upon the plate 24. A clutch 48 is associated with the carbon 34 in such a manner that when the clutch is raised at one side by a connecting link 50, teeth 52, which are rigidly mounted in the clutch and positioned on each side of the carbon, will grip the carbon and move the same therewith. The teeth 52 are preferably constructed of some hard insulating material such as lava, flint or the like.

70 Pivots attached to the upper end of the link 50 is one leg of a substantially U shaped element 54, both legs of which are shown best in Figures 6 and 7. The other leg of the member 54 is rigidly mounted upon one end of a lever 56 which in turn is pivotally connected to the lower portion of a lug 58 at the point 60. The other end of the lever 56 is free and rests loosely upon a cam 62. Curved faces 63 of the lever 56 co-operate with the cam. One portion of the cam is pivotally mounted upon a support 64 which is mounted on the plate 24. Another portion of the cam is pivotally connected to one end of a link 66, the other end of the said link being pivotally attached to a lever 68, positioned immediately above the lever 56. One end of the lever 68 is pivotally mounted upon the upper portion of the lug 58. Hence it is obvious that upon an upward movement of the lever 68, by the suitable cam and lever mechanism, described above, the lever 56 and hence the carbons 42 will also raise, but not at the same rate as the actuating lever 68.

75 Referring particularly to Figures 1 and 3, a pair of solenoids 70 is mounted upon the back of the plate 24 and slidably positioned in the axial center of each is a magnetic core 72. A flat bar 74 is rigidly 105 attached to and forms an extension of the lower end of the core 72. The bar 74 is also constructed of a magnetic metal and is adapted to slide adjacent the poles of a magnet 76, the said magnet being energized by 110 means of a coil 78, connected in series with the solenoid 70. A strip of non-magnetic material, preferably metal, is positioned between the poles of the magnet 76 and the bar 74 to provide a gap between the two elements and hence decrease the magnetic pull upon the bar. Upon energizing the solenoid 70, the core 72 is moved by means of the magnetic flux set up therein, but the coil 78 being energized at the same time causes a 115 flux to be set up in the magnet 76 which in turn attracts the bar 74 and provides a damping means for the motion of the core. A means for varying the damping effect of the magnet 76 upon the bar 74 comprises a pair of set screws 80 and 82, the screw 80 adapted to frictionally engage the side of the bar 74, the other screw 82 similarly engaging the edge of the said bar.

120 Rigidly connected to the upper portion of

the core 72 is a non-magnetic metallic rod 84 which in turn has mounted upon its upper end a strip of resilient metal 86 positioned at right-angles to the said rod. The outer end 5 of the strip 86 is rigidly attached to a U shaped connecting element 88, the other end of which is attached to one end of a second resilient strip 90 parallel to the first strip. The other end of the strip 90 is rigidly 10 mounted upon the lever 68. Thus it is seen that the motion of the core 72 is flexibly transmitted through this above described resilient connection to the combination cam and lever carbon feed mechanism and hence 15 to the movable carbons 42.

The energizing current for each set of carbons 34 and 42 and each carbon feed mechanism 70, 72, 68 etc., is brought in through an opening in the cap 18, the said opening 20 being provided with an insulating bushing 92. A duplex lead 94 is connected at one end to a suitable source of current, such as the house current or the like. The inner end of one of the conductors of the duplex 94 is 25 connected to the screw 40 which, as has been described above, is electrically connected to the clamp 32 and hence to the fixed carbon 34. The other conductor of the duplex 94 is connected to an insulated binding post 96, 30 the insulation comprising a mica washer or bushing 98. The current is carried therefrom to the solenoid 70 by means of a conductor 100, thence to the magnet coil 78 by a conductor 102, through the coil 78 and 35 thence through wire 103 to a terminal 104. A bus bar 106 extends from the terminal 104 outwardly through an insulating bushing 108 positioned in an opening in the cap 18. A bead insulated flexible conductor 110 then 40 connects the other end of the bus 106 to a U shaped clip 112 which frictionally grips the upper end of the movable carbon 42.

The clip 112 is constructed of a metal which contracts when heated and hence 45 when the carbon 42 is heated the clip grips the carbon tighter instead of expanding and loosening its grip upon the carbon, as it would if made of the ordinary metal heretofore used on such devices.

50 A modification of the clip is shown at 114 in Figure 9, the said clip being mounted upon the carbon 42 at right-angles to the same, distinguishing from the clip 112 which clips over the top of the carbon pencil.

55 One circuit has been described above, but as shown best in Figure 3, two such circuits comprise the unit, each being connected as described, but in no way interconnected. Therefore, the device may be operated with 60 a single carbon or with double carbons as desired.

It is apparent that herein is provided a device which is flexible, efficient and possesses extremely rugged characteristics.

65 The device is simple to operate, being prac-

tically automatic throughout, the manual adjustments being reduced to a minimum. The device as a whole is constructed with a view particularly to being operated by a person inexperienced and unfamiliar with technical and electrical operations and principles.

I am aware that many changes may be made and numerous details of construction varied throughout a wide range without departing from the principles of this invention, and I therefore do not purpose limiting the patent granted hereon otherwise than as necessitated by the prior art.

I claim as my invention:

1. In an arc lamp, a damper for the carbon feed mechanism comprising a solenoidally operated plunger connected to said feed mechanism, and magnetically operated damping means for said plunger, said magnetically operated damping means comprising an electro-magnet, and an extension on the end of the plunger, the said extension adapted to slide adjacent the poles of the magnet.

2. In an arc lamp, a damper for the carbon feed mechanism comprising a solenoidally operated plunger connected to said feed mechanism, and magnetically operated damping means for said plunger, said magnetically operated damping means comprising an electro-magnet, an extension on the end of the plunger, the said extension adapted to slide adjacent the poles of the magnet, and means for providing a magnetically inactive gap between the poles and the extension.

3. In an arc lamp, a damper for the carbon feed mechanism plunger connected to said feed mechanism, and magnetically operated damping means for said plunger, said magnetically operated damping means comprising an electro-magnet, an extension on the end of the plunger, the said extension adapted to slide adjacent the poles of the magnet, and means for providing a magnetically inactive gap between the poles and the extension, said means including a strip of non-magnetic material mounted upon the pole faces.

4. In an arc lamp, a damper for the carbon feed mechanism comprising a solenoidally operated plunger connected to said feed mechanism, and magnetically operated damping means for said plunger, said magnetically operated damping means comprising an electro-magnet, an extension on the end of the plunger, the said extension adapted to slide adjacent the poles of the magnet, and means for providing a magnetically inactive gap between the poles and the extension, said means including a strip of non-magnetic material mounted upon the pole faces, and additional means for varying

the proximity of the extension and the said non-magnetic strip.

5. In an arc lamp, a damper for the carbon feed mechanism comprising a solenoidally operated plunger connected to said feed mechanism, and magnetically operated damping means for said plunger, said magnetically operated damping means comprising an electro-magnet, an extension on the 10 end of the plunger, the said extension adapted to slide adjacent the poles of the magnet, and means for providing a magnetically inactive gap between the poles and the extension, said means including a strip 15 of non-magnetic material mounted upon the pole faces, and additional means for varying the proximity of the extension and the said non-magnetic strip, said additional means comprising a plurality of set-screws 20 operatively associated with the extension.

In testimony whereof I affix my signature.

ALBIN HJELM.
